UNITED STATES PATENT OFFICE

HARRY C. CLAYBURGH, OF OAKLAND, CALIFORNIA, ASSIGNOR TO DAWSON MANUFACTURING COMPANY, OF OAKLAND, CALIFORNIA

CAN LIFTER

Application filed August 1, 1930. Serial No. 472,303.

This invention is for a can lifter and has special reference to a hand operated device for gripping and lifting a plurality of cans, such as the usual containers for food products, and has for its main object, the provision of a hand operated device which is normally in open position, and can thus be placed over a plurality of cans and then, by means of a gripping action on the handle is caused to grip the cans, whereby they may be lifted and placed in suitable cases or otherwise disposed of, the can being released as soon as the gripping action on the handle is released.

Another object of the invention is to provide a device of the class described which will grip the cans transversely or across the end by means of a three-point grip, thereby equally spacing the cans and properly aligning them, whereby they may readily and conveniently be placed in cases, or stacked, in an orderly manner, and in an upright position.

Further objects of the invention will be readily discernible as the following description is read on the drawings forming a part of this specification.

The invention consists primarily of a pair of parallel spaced gripping bars, having a lifting and gripping handle centrally spanning the bars whereby a gripping action on the handle causes the bars to close toward each other, one of the bars having an inturned flange adapted to cooperate with a can just below the head-seam, the other bar being provided with a plurality of spaced discs vertically pivoted and in horizontal alignment with the inturned flange on the opposite bar, the cans being each gripped between the inturned flange on one bar and two discs on the opposite bar providing thereby a three-point grip.

The invention is adequately illustrated in the accompanying drawings in which;

Fig. 1 is a top plan view of the invention.

Fig. 2 is a side elevation, and,

Fig. 3 is an end elevation of the invention.

Similar reference characters are used to designate similar parts throughout the several views.

The invention consists of a channel shaped bar 5 the lower flange 6 of which is shorter

than the upper flange 7. Parallel to the channel shaped bar and spacedly related thereto is an angle bar 8, the horizontal leg 9 being turned inward and having mounted thereon, a plurality of spacedly related spools 10 having a flange 11 at the bottom thereof and pivotally mounted by means of screws 12 which are threadedly engaged in the flange 9 and locked in adjusted position by means of the nut 13. Integral with or fixed to the bar 5 are stop fingers 14 adapted to prevent the bar 5 from passing too far down the sides of the cans 15 and possibly cooperating with the upper flange 7.

The handle consists of a pair of cooperating members 18 and 19 fixed respectively to the upper flange 7 and vertical leg 8 of the gripping bars as indicated at 16 and 17 and pivotally connected at 20, the member 18 having the finger guard 21 integral therewith and extending substantially parallel to the top bar 22 of member 19, whereby a grip may be obtained by placing the palm of the hand over bar 22 and the fingers through the guard 21.

The operation of the device is as follows: The device is placed over the tops of a plurality of cans and the flanges 6 and 11 permitted to drop over the edges and below the cap seam as indicated in Figs. 1 and 3. The pivoted members 11 centralize the cans with reference to each pair of flanges 11. By drawing the finger guard 21 toward the bar 22, the cans are caused to be gripped between the flange 6 and pivoted flanges 11, thus gripping at three points and securely holding the cans, which may then be lifted while retaining the grip on the handle. To release the cans it is but necessary to release the grip between finger guard 21 and bar 22, the device being instantly removable.

Having described an operative method of constructing and operating the device, it will be understood that variations in construction and arrangement of parts which are consistent with the appended claims may be resorted to without detracting from the spirit or scope of the invention or sacrificing any of its advantages.

What I claim is:

1. A can lifting device, in combination a

bar having an inturned flange, a second bar in spaced relation and provided with a plurality of depending equally spaced, pivotally mounted spools, said bars being respectively fixed to a pair of co-acting, pivotally connected members of a gripping handle, said inturned flange and the flanges on said spools being adapted to engage a plurality of cans at three points each, just below the cap seams thereof.

2. A can lifting device comprising, a bar having an inturned flange, a second bar in spaced relation and parallel thereto, and provided with a plurality of equally spaced pivotally mounted discs said bars being connected by means of pivotally connected co-acting members of a gripping handle, whereby the gripping of said coacting members causes said cans to be gripped between said inturned flange and a pair of said discs.

3. A can lifting device comprising a pair of spacedly related parallel bars intermediately connected by means of a carrying handle consisting of two coacting members pivotally connected, one of said bars having an inturned flange, the other of said bars having a plurality of equally spaced pivotally mounted discs in substantially horizontal alignment with said flange, the coacting members of said carrying handle being adapted to create a gripping action between said flange and said discs on an interposed can about the cap seam.

4. A can lifting device comprising a pair of spacedly related bars intermediately connected by means of a carrying handle consisting of two coacting members pivotally connected, an inturned flange at the lower end of one of said bars, the other of said bars being provided with a plurality of equally spaced discs pivotally mounted and in horizontal alignment with said inturned flange, and spacers between said discs and said bar.

5. A can lifting device, in combination parallel members adapted to diametrically span a plurality of cans, one of said members having means for coincidentally spacing said cans and engaging the undersurface of the cap seam, the other member being adapted to engage the under surface of the cap seam, said members being fixedly connected to handle members, and a handle comprising two members hingedly connected and adapted by gripping thereof to retract said parallel members.

6. A can lifting device, a pair of hingedly connected, cooperating handle members, a bar transversely fixed to each of said members and parallel one to the other, a plurality of spaced can spacing and gripping devices secured to one of said bars, said other bar having an inturned flange adapted to cooperate with said gripping devices for supporting a plurality of spaced cans by the cap seams thereof.

7. A can lifting device, in combination, two parallel members transversely connected by a gripping handle adapted by the gripping thereof to move said parallel members toward each other, one of said members having an inturned flange throughout the length thereof, the other of said members having a plurality of spaced discs mounted on vertical axes and in horizontal alignment with said inturned flange.

8. A can lifting device, in combination, parallel bars retractably mounted and an intermediately disposed handle therefor, one of said bars having continuous means throughout its length for engaging the cap seam of a can, the other bar having spaced members in horizontal alignment with said continuous means adapted to each coincidentally space and engage two cans by the cap seams thereof.

In testimony whereof I affix my signature.

HARRY C. CLAYBURGH.
